US0D1025126S

(12) **United States Design Patent** (10) Patent No.: **US D1,025,126 S**
 Ciardi et al. (45) Date of Patent: ** Apr. 30, 2024

(54) **DISPLAY SCREEN OR PORTION THEREOF WITH GRAPHICAL USER INTERFACE**

(71) Applicant: **IGT**, Las Vegas, NV (US)

(72) Inventors: **Emilia Ciardi**, Lavena Ponte Tresa (IT); **Jorgen Johnson**, Las Vegas, NV (US); **Allan Snippen**, Reno, NV (US); **Matthew Tarbox**, Reno, NV (US); **Tamer Uz**, Reno, NV (US)

(73) Assignee: **IGT**, Las Vegas, NV (US)

(**) Term: **15 Years**

(21) Appl. No.: **29/917,610**

(22) Filed: **Nov. 21, 2023**

(74) *Attorney, Agent, or Firm* — Neal, Gerber & Eisenberg LLP

(57) **CLAIM**

The ornamental design for a display screen or portion thereof with graphical user interface, as shown and described herein.

DESCRIPTION

The file of this patent contains at least one drawing/photograph executed in color. Copies of this patent or patent application with color drawing(s)/photograph(s) will be provided by the Office upon request and payment of the necessary fee.

The FIGURE is a front view of a display screen or portion thereof with graphical user interface showing our new design.

The dashed broken line perimeter in the drawing illustrates a display screen or portion thereof and forms no part of the claimed design.

1 Claim, 1 Drawing Sheet
